[57] CLAIM

The ornamental design for a bottle for lotion, as shown and described.

DESCRIPTION

FIG. 1 is a front view of a bottle for lotion showing my new design;

FIG. 2 is a top plan view thereof;

FIG. 3 is a bottom plan view thereof;

FIG. 4 is a left side view thereof, the right side view being a mirror image thereof;

FIG. 5 is a front view thereof in which the cap is removed for completeness of illustration; and,

FIG. 6 is a perspective view thereof in which the cap is removed for completeness of illustration, the opposite side view being a mirror image thereof.
